UNITED STATES PATENT OFFICE.

JOSEPH E. SAUNDERS, OF OVID, COLORADO.

CENTRIFUGAL WATER-LIFTING PUMP.

981,007.

Specification of Letters Patent. Patented Jan. 10, 1911.

Application filed November 19, 1909. Serial No. 528,963.

To all whom it may concern:

Be it known that I, JOSEPH E. SAUNDERS, a citizen of the United States of America, residing at Ovid, county of Sedgwick, and 5 State of Colorado, have invented a new and useful Centrifugal Water-Lifting Pump, of which the following is a specification.

My invention relates to improvements in centrifugal water lifting pumps, and the 10 objects of my invention are: First—to provide a centrifugal water lifting pump that will raise water by the centrifugal action of a rapidly rotating conical cylinder. Second—to provide a pump that will raise 15 water by centrifugal force and in which the discharging water is used to develop power, which is applied to assist in operating the pump; and Third—to provide a simple, inexpensive, durable and practical rotary centrifugal pump that does not contain any 20 incased rotating or reciprocating parts, and that is especially adapted to pump or raise water for irrigation and other purposes. I 25 attain these objects by the mechanism illustrated in the accompanying drawings, in which:

Figure 1 is a plan view of the improved centrifugal water lift. Fig. 2 is a vertical sectional view through the same. Fig. 3 is a 30 bottom plan view of the supplemental power imparting water wheel. Fig. 4 is a plan view of the rotatable conical casing. Fig. 5 is a plan view of the intake box. Fig. 6 is a front view of the same; and Fig. 35 7 is a side view of the adjustable water-dividing blades.

Similar letters of reference refer to similar parts throughout the several views.

Referring to the drawings: the numeral 40 1 designates the water intake conduit of my centrifugal pump. This intake conduit may be a pipe or a box shaped intake. I preferably make it in the form of a flat box shaped tube and provide it with an outlet 45 pipe portion 2, which projects from the top of its opposite end. This outlet pipe 2 of the inlet box 1, is provided with a hollow tubular central stem portion 3, upon which a hollow hub 4 is slidably mounted, which 50 supports a pair of water dividing blades 4^A. These blades are secured to or are formed on the opposite sides of the hollow hub 4, and their outer ends extend loosely between ribs 6 formed on the inside of the outlet 55 pipe 2 that form slideway spaces for them in the water intake box. These water divid-

ing blades are arranged to extend diametrically across the outlet pipe's orifice, and they are made to be moved slidably upward from the bottom of the intake box to a number of inches above it, and they are adapted to prevent water, as it is drawn up into the conical water lifting tube, from swirling into a ring shaped column in the outlet pipe portion of the intake box.

A hand operating rod 6^A is provided for lifting the water dividing blades. This rod is secured at one end to the blades and extends up through the water box above the water and is provided at its upper end with a handle portion 6^B. This rod may be secured to hold the blades in any desired adjusted position by any suitable means, such as by a pin 6^C that is adapted to rest on a cleat 6^D and to be inserted in a row of holes 6^E formed in the rod 6^A. The hollow tubular stem 3 is secured to the bottom of the water intake box and is arranged to form a guide bearing for the lower end of a vertically supported shaft 8 which extends 75 loosely through it and is journaled in any suitable journal box 6^F, which may be secured to and supported on any suitable foundation such as stone or concrete foundation or a wooden frame or a timber. The 80 upper end of this shaft 8 is supported by a bar 8^A, secured to cross bars 9 of a wooden or metal frame 10.

A journal box 11 is secured to the bar 8^A and the upper end of the vertical shaft 90 8 is rotatably journaled in the box 11. Upon this shaft 8 a vertically positioned conical 95 casing 12 is mounted, which may be made of any suitable material such as galvanized iron or steel or sheet or cast iron or other metal, and it is secured to the shaft by any suitable means such as set screws 13, which are threaded through hub portions 14, which are formed on spider arms 15, that extend from and are secured to the inner peripheral wall 100 of the conical casing. These spider arms 15 are preferably placed at the upper and lower portions of the conical casing. This conical casing is arranged with its apex or smallest diameter portion at its lower end and this lower end portion is provided with a tubular inlet portion 17, which is arranged to extend loosely over the projecting pipe outlet portion of the intake box, and at the entrance of this inlet 17 I place four vane-blades 18 at the quarter points of the interior surface of the tube. The vane-blades

are adapted to force the water to rotate at the same speed as the casing, and they are secured in any suitable manner to the interior of the conical casing, and they are 5 adapted to be placed at the lower end portion of it, preferably at its lowest portion, and they extend any predetermined distance along the interior of the casing. This conical casing may be of any desired degree of 10 taper and its larger top end may be of any desired larger diameter relative to its intake lower end, and it may be of any desired length. I find in practice, however, that this casing may be given a taper sufficient to make 15 its upper end several times the diameter of its lower end and lift water in a strong stream when rotated at a high rate of speed, but this taper may be varied considerably to suit higher or lower rotative speeds of the 20 casing. The top of this casing is provided with a partial cover-like rim portion 21, which preferably slopes upward in conical form and is arranged to leave an opening through its top portion into the interior 25 of the casing. The top peripheral edge of the casing is provided at equidistant points throughout its circumference with water discharging pipes 23. These discharge pipes are arranged to discharge the 30 water raised by the centrifugal movement in jets against a supplementary or auxiliary power imparting device, which is loosely mounted on the driving shaft 8 of the casing and assists in driving the driving shaft and its 35 casing through the medium of the discharging water, as will be presently described. The upper end of the casing is surrounded by a stationary water receiving trough 24, which is preferably circular and is substantially 40 rectangular in cross section and is provided with a discharge pipe 25, which is arranged to lead the water to any predetermined point away from the casing. The top edge of this trough is provided with an upwardly inclined rim portion 26, which is adapted to cover the felly portion of a supplementary power imparting wheel 27, which is driven by the discharging jets of 45 water from the top of the casing, as will be presently described. The vertical driving shaft 8 extends above the casing and upon it I mount and secure to it by any suitable means a power driving wheel 28. This power driving wheel 28 is preferably a belt 50 driven sheave wheel, but may be a sprocket chain wheel or a bevel gear, if desired.

The wheel 27 comprises a slightly dished or conical disk 29 and a ring 30, between which are secured a plurality of impact blades 31, which are adapted to be engaged by the jets of water escaping through the pipes 23. The wheel 27 is secured to a sleeve 32, which is loosely mounted upon the shaft 8, and may be provided with ordinary ball bearings if 55 desired. The lower end of the sleeve has a

flange 33, which is connected with the disk 29 by a plurality of radiating brace rods 34. The ring 30 of the wheel 27 encircles the upper end of the cone 12, so that the blades 31 and ring 30 lie within the trough 24. A 7 sheave wheel 35 is secured upon the upper end of the sleeve 32. The blades 31 are preferably curved blades, though they may be made straight, if desired, and they are arranged to receive the impact of the discharging jets of water that are forced from the rotating cone by its centrifugal force through the water discharging pipes 23 at its top edge. These bucket blades are arranged directly opposite to and in alignment with the discharging jets of water, and they are preferably curved toward the discharging jets of water so that they will offer a right angled surface for the jets to strike against, as they move away from them. A 8 sufficient interval is left between the bucket blades to allow the water after impinging against them to pass freely out from them into the trough.

The shaft driving wheel 28 and the 90 power transmitting wheel 35 of the water wheel 27 are connected by belts 36 and 37 to similar power transmission wheels 38 and 39, which are mounted on a counter shaft 40, upon which a power driving 95 wheel 41 is secured. This counter shaft is journaled in boxes 42, which are secured to parts of the frame. The wheel 41 is driven by a belt from any suitable source of rotating power, such as by a windmill or 100 by horse power or by hand power or by steam, electric or other suitable power.

The operation of my new centrifugal pump is as follows: The intake box and lower end of the conical casing are set in a 105 body of water deep enough to extend above the intake box. The counter shaft is driven by its driving wheel 41, and rotative power is imparted to the vertical shaft from the counter shaft through the belt 36, and sheave 110 wheels 28 and 38, thus rotating the conical casing. A high rate of rotative speed is given to the vertical shaft and to the casing. This speed, however, may vary with the height of the lift or length and inclination 115 of the sides of the casing. The high speed rotative movement of the casing rotates the water and throws it by centrifugal force around and up the inclined inner peripheral surface of the casing to its upper top rim portion, from which it is discharged in the 120 form of jets through the discharge pipes 23 against the bucket blades 31 of the water wheel. This circumferential row of discharging jets has force enough to drive the 125 water wheel rotatively at a high rate of speed and with considerable power, which power is transmitted by its power wheel through the belt 37 to the sheave wheel 39 on the counter shaft and assists the counter 130

shaft to drive the casing. The water dividing vertically slidable blades 4^a in the intake box prevent the water as it is drawn into the discharge tube 2 of the intake box 5 from being swirled into a ring shaped body of water, which must naturally assume this form of a column under the centrifugal action of the casing and which would reduce the volume of inflowing water flowing 10 from the intake box through its outlet pipe portion into the lower end of the casing, which is also provided with water dividing blades for the purpose of forcing the water to rotate at the same speed as the 15 casing. The vertically sliding blades permit of a vertical positioning of these blades relative to the speed of the casing to thoroughly break up any swirling action of the water in the outlet pipe of the water 20 intake box.

My invention provides a simple, positive and thoroughly practical and inexpensive pump for lifting water in which the centrifugal force of the discharging water 25 drives a wheel that adds a constant supply of power to its operations and decreases the amount of power required to operate it by the amount of power its discharging water jets develop in the water wheel which 30 they drive.

My improved pump is entirely free from interior rotating parts, moving pistons, valves or packed parts, and is not apt to get out of order or require repairs, and 35 while I have illustrated and described the preferred construction and arrangement of my improved pump, I do not wish to be limited to them, as many changes might be made without departing from the spirit of 40 my invention.

My improved pump is illustrated in my pending application for a method of raising water, filed November 19, 1909, Serial Number 528,962.

Having described my invention, what I claim as new and desire to secure by Letters Patent is:

1. In a centrifugal pump, the combination with an inverted, conical casing having 50 outlets at its upper end and means for rotating said column, of a water intake conduit having an outlet communicating with the lower end of the said column; slideways in said outlet; water dividing blades in said 55 slideways; and means including a manually operated rod for adjustably raising and lowering said blades.

2. In a centrifugal pump, the combination of a water intake tubular box provided 60 with an outlet tubular portion, water dividing blades slidably mounted in said tubular outlet portion of said intake box, and means including a rod secured to said blades for adjustably setting said blades in any pre- 65 determined position in the outlet tube of

said intake box, with an inverted, conical casing rotatably journaled to the outlet portion of said intake box and provided with a water inlet registering with the water outlet of said intake box, a plurality of water 70 dividing blades in the lower end portion of said casing adjacent to the outlet portion of said inlet box, means for discharging water from the top end portion of said casing, and means for rotating said casing at a speed sufficient to draw and raise and discharge a stream of water into and out of said casing by the centrifugal action 75 of the rotary motion of said casing.

3. In a centrifugal pump, the combination of a water inlet pipe provided with an outlet pipe portion, an adjustable partition in said outlet pipe portion of said water inlet pipe adapted to prevent circular movement of the water passing through said outlet pipe portion of said inlet pipe, a vertical shaft extending loosely through said outlet portion of said inlet pipe, a supporting frame for said shaft and intake pipe, an inverted, conical casing mounted on and 80 secured to said shaft having an inlet aperture at its smaller end registering with the outlet aperture of said inlet pipe, a circumferential row of water discharging pipes at the upper larger end portion of said conical 85 casing, a fixed trough surrounding said discharge pipes arranged to receive water therefrom and provided with an outlet pipe, means for rotatably supporting said shaft and conical casing in a vertical position, and 90 means including a power receiving and transmitting wheel mounted on and secured to said shaft for rotating said casing.

4. In a centrifugal pump, the combination of a supporting frame, a shaft vertically supported in said frame on suitable bearings, a water inlet tube provided with an outlet tubular portion and adapted to be mounted on the lower end portion of said shaft and to be immersed in a body of 100 water, said tubular outlet portion of said inlet tube being provided with a central hub portion through which the lower end of said shaft revolvably extends, a sleeve 105 slidably mounted on said hub portion of said inlet tube, diverging blades on said sleeve extending diametrically across said outlet tubular portion of said inlet tube, a rod secured at one end to one of said blades and extending up through said inlet tube 110 and through and above said body of water, a hand grasping portion on the upper and opposite end of said rod for raising or lowering said rod and blades on said hub, means for securing said rod and blades in 115 predetermined positions on said hub, with an inverted conical casing mounted on and secured to said shaft and provided with its smaller end open and fitting over said inlet tube's outlet tubular portion, radial blades 120

secured to the inner walls of said casing and extending diametrically toward said shaft a predetermined distance, means for discharging water from the top of the end 5 portion of said casing and means including power transmitting wheels for rotating said casing.

5. In a centrifugal pump, the combination with an inverted, conical casing having outlets at its upper end, and means for rotating said column, of a fixed intake having an outlet pipe, adapted to enter the lower end of said column; adjustable vertically disposed blades in said outlet pipe; 15 and upright blades in the lower end of the column surrounding said outlet pipe.

6. In a centrifugal pump, the combination with an inverted conical casing having inwardly projecting upright blades at its

lower end, and outlets at its upper end, of 20 a fixed intake having an outlet pipe which extends into the lower end of said casing; a bearing tube in the intake in axial line with the outlet thereof and extending into the same; a shaft mounted in bearings at 25 its upper end and extending through said casing and the said bearing tube; oppositely positioned blades slidably and adjustably mounted on the bearing tube; arms rigidly connected to said shaft and to the 30 casing; and a pulley on said shaft adapted to be connected with a source of power.

In testimony whereof I affix my signature in presence of two witnesses.

JOSEPH E. SAUNDERS.
